UNITED STATES PATENT OFFICE.

LORENZO D. B. SHAW, OF NEW YORK, N. Y.

HYDRAULIC ENGINE.

SPECIFICATION forming part of Letters Patent No. 653,461, dated July 10, 1900.

Application filed July 10, 1899. Serial No. 723,298. (No model.)

To all whom it may concern:

Be it known that I, LORENZO D. B. SHAW, a citizen of the United States, and a resident of New York, (Coney Island,) in the county of 5 Kings and State of New York, have invented certain new and useful Improvements in Hydraulic Engines, of which the following is a specification.

The object of my invention is to produce an 10 engine in which water is the motive power.

The invention consists of two cylinders communicating with each other by a chamber or passage at each end, each cylinder containing a sliding cylinder of smaller diameter and 15 about the same length, which are free to slide in suitable guides and act as valves for regulating the induction and eduction of the fluid to act upon pistons contained and working in said sliding cylinders, both pistons traveling 20 in the same direction, they being connected to a cross-head that by a pitman is connected to a crank on the driving-shaft, which also carries eccentrics that operate the inner cylinders or valves.

25 Referring to the accompanying drawings, Figure 1 represents an end elevation of an engine embodying my invention. Fig. 2 is a side elevation of same. Fig. 3 is a longitudinal vertical section through the cylinders. Fig. 4 is 30 a side view of one of the sliding cylinders or valves. Fig. 5 shows, respectively, a plan and elevation of one of the valve seats and guides.

A represents a base-piece upon which are 35 mounted two cylinders B B', the upper ends of which are closed by a cap or cover C. The cylinders are each provided with a pipe D D' for the induction and eduction of the fluid. The base A and cap C are each provided with 40 a passage a c, so as to form a communication between the cylinders at each end, and the cap C is also provided with suitable stuffing-boxes e d for the piston-rods and valve-stems. The inner faces of the base-piece and cap are 45 recessed down opposite the end of each cylinder to receive the valve-seats F F'. The bases of these valve-seats are slightly larger than the internal diameter of the cylinders B B', so that they are held in position by the 50 base-piece A and cap C. The valve-seats are provided with prongs or projections f f, that act as guides for the sliding cylinders or

valves G G', which are free to work up and down and are operated by valve-stems H and connected by rods h h to cranks or eccentrics J on a crank-shaft I, the crank I' of which is, by a pitman I², connected to a cross-head I³, to which the piston-rods K are connected.

In each of the sliding cylinders G is fitted a piston K², secured to the end of the rod K, 60 the upper end of which is secured to the cross-head I³, operated by the crank I through pitman I².

As the sliding cylinders G G' operate to admit or cut off the supply of fluid the space between the prongs f f on the valve-seat F form ports for the fluid to pass through when the ends of the cylinders are within the inner faces of the valve-seats F.

The operation is as follows: The engine being in the position shown in the drawings—that is, with the pistons at half-stroke and the cylinder or valve G down, so as to admit the fluid on the upper side of the pistons K², and the other cylinder or valve G raised, so 75 that fluid can pass out at its lower end—now supposing the fluid to be entering by the pipe D it takes an upward course in the direction of the arrows 1 and passes through the valve-seat into the passage c and exerts an equal 80 pressure upon the upper end of both the pistons K², which are thus caused to descend, and through the cross-head I³, connecting-rod, and crank I' transmits a rotary motion to the shaft I, which by means of the eccentrics J 85 causes the positions in the cylinders G G' to be reversed, so that the fluid will pass down to the under side of the pistons K² and cause them to be raised. The fluid that was in the chamber a will in the meantime have passed 90 in the direction of the arrows 2 and be exhausted out of the pipe D'; but a certain proportion of the fluid will always be left in the chambers a and c, so that as soon as the sliding cylinder or valve G is moved to admit the 95 fluid at either end there will not be any lost motion, as the incoming fluid will at once act upon the fluid that is retained in the chambers, and thus at once exert pressure upon both pistons simultaneously.

100 It will be found that with an engine constructed as described great power and speed are obtained. The inner cylinder or valve being contained in the pressure, it is perfectly

balanced, the friction is reduced to a minimum, and there is nothing that can get out of order. Thus the engine will last a long time with very little care.

5 What I claim is—

In an engine the combination of two pistons moving in the same direction, sliding cylinders or valves reciprocating in opposite directions and in which said pistons work, one of

said cylinders or valves acting as a supply and the other as an exhaust substantially as set forth.

In testimony whereof I have affixed my signature in presence of two witnesses.

LORENZO D. B. SHAW.
